UNITED STATES PATENT OFFICE.

X LA MOTTE SAGE AND FREDERICK T. MCINTYRE, OF NEW YORK, N. Y.

PORTABLE BURGLAR-ALARM.

SPECIFICATION forming part of Letters Patent No. 624,982, dated May 16, 1899.

Application filed March 25, 1898. Serial No. 675,174. (No model.)

To all whom it may concern:

Be it known that we, X LA MOTTE SAGE and FREDERICK T. MCINTYRE, citizens of the United States, residing at New York, in the 5 State of New York, have invented a new and useful Portable Burglar-Alarm, of which the following is a specification.

Our invention relates to burglar-alarms, and more especially to devices of this class of 10 a construction and size to permit of their being carried in the pocket, the object of our invention being to construct a portable burglar-alarm which may be quickly attached to a door-casing, window-frame, transom-casing, 15 or any like fixed support by the side of an opening door or window in such manner and position that the opening of the door or window will actuate the alarm to explode an ordinary paper cap.

20 With this object in view our invention consists in the improved construction, arrangement, and combination of parts hereinafter fully described and afterward specifically pointed out in the appended claim.

25 In order to enable others skilled in the art to which our invention most nearly appertains to make and use the same, we will now proceed to describe its construction and operation, reference being had to the accompanying drawings, forming part of this specification, in which—

30 Figure 1 is a perspective view illustrating a burglar-alarm constructed in accordance with our invention. Fig. 2 is a central vertical section through the same.

Like letters of reference mark the same parts wherever they occur in the drawings.

Referring to the drawings by letter, A indicates a hollow casing or frame open at the 40 bottom and both ends and provided at the end of one of its sides with projecting lugs B. One end of the casing is provided with a longitudinal slot C, extending to about the middle of the top of the casing, as shown at C'. The 45 top also has a hole or perforation D and three triangularly-arranged points E.

F indicates a bent arm or hammer provided with bifurcated arms G, pivoted at their inner ends to the lugs B.

50 H indicates a spiral spring secured at its outer end to the hammer F and passing

through the slot C and secured at its inner end to a pin I, projecting inwardly from the casing A.

J indicates the central bulb or button of 55 explosive matter, inclosed in paper J' and known as a "paper cap" for toy pistols. This cap is placed in position by impaling the paper J' upon the pins E. A small notch K is cut in the bottom of one of the arms G. A 60 curved trigger R is pivotally secured within the casing and projects some distance beyond its opposite end. A curved lever M, of similar shape to the trigger, is also pivoted within the metal casing and has its inner end under 65 the inner end of the trigger and its outer end passing through the slot C and engaged in the notch K.

The relative positions of the hammer F and spring H are such that when the hammer is 70 drawn into the position shown in Fig. 2 the direct line of pull of the spring upon the hammer is a straight line between the point of connection of the spring to the hammer and to the pin I, and such line falls beyond the 75 pivotal point of the hammer in the lugs B. As a consequence the hammer will be held in that position as long as desired, the end of the lever M resting in the notch K and preventing its further movement backward. 80

It will be understood that the trigger R is designed to project beyond the edge of the door-casing in the path of the moving door.

The advantages attending the use of our invention are numerous, the alarm being 85 extremely light, portable, and cheap. It can be readily attached and detached at points where the slightest attempt to remove any door, window-sash, shutter, transom, or the like will be immediately followed by an explosion 90 sufficiently loud to waken a sleeper or call the attention of a person in a distant part of the house. The expense of the particular ammunition which we use is nominal, such explosives being in common use and very 95 cheap.

While we have illustrated and described the best means now known to us for carrying out our invention, we do not wish to be understood as restricting ourselves to the exact 100 details of construction shown, but hold that any slight changes or variations such as

might suggest themselves to the ordinary mechanic would properly fall within the limit and scope of our invention.

It is obvious that instead of having ears or 5 lugs turned up from the case and a spring arranged upon the top of case, we may cut away one end of the case and have the hammer pivoted in such cut-away end and the spring arranged within the case without de- 10 parting from the principle of our invention.

Having thus fully described our invention, what we claim as new, and desire to secure by Letters Patent of the United States, is—

In a burglar-alarm, the combination of the 15 metal casing, open at the end and provided with projecting lugs and a longitudinal slot, a hammer having bifurcated arms pivotally

secured to the lugs, a spring passing through the elongated slot and secured at its ends to the hammer and casing respectively, a lever 20 pivotally attached within the casing, having one end projecting through the longitudinal slot and bearing under the hammer, and a trigger pivotally mounted in the casing, having its inner end in engagement with the inner end of the lever and its outer end project- 25 ing beyond the casing, substantially as de- scribed.

X LA MOTTE SAGE.
F. T. McINTYRE.
